UNITED STATES PATENT OFFICE.

ALBERT PULVERMACHER, OF SONNEBERG, GERMANY.

DOLL.

SPECIFICATION forming part of Letters Patent No. 447,034, dated February 24, 1891.

Application filed September 29, 1890. Serial No. 366,484. (No model.)

To all whom it may concern:

Be it known that I, ALBERT PULVERMACHER, a citizen of the German Empire, residing at Sonneberg, Germany, have invented certain new and useful Improvements in Dolls; and I do hereby declare the following to be a full, clear, and exact description of the invention, such as will enable others skilled in the art to which it appertains to make and use the same.

10 The jointing of jointed dolls has usually been effected heretofore by means of rubber cords and twine drawn across the inside of the doll's body and tied together in the state of tension. This operation is particularly difficult and requires special skilled workmen, (called "embossers.") If during the use of the doll the cord breaks, or if the head or other part of the body is broken, the doll comes to pieces, and one not skilled will hardly be able 15 to mend such doll and repair it by replacing the defective parts, for it is not easy to tie up the rubber in the correct manner without injuring the hair of the doll. It is self-evident that this old-fashioned articulation, though 20 simple in appearance, is expensive in manufacture, as comparatively high wages have to be paid for this kind of work. In order to obviate these inconveniences and to produce a joint that any one can set up and one of low 25 price, I have made use of the characteristic properties of spiral springs. A spiral spring is not only elastic, but can also be used as a 30 screw.

35 My invention consists, mainly, in the combination of such springs with the jointed parts of the dolls and transverse pins arranged therein, as hereinafter more particularly set forth and claimed.

40 In the accompanying drawings, Figure 1 represents a vertical section of an entire doll constructed according to my invention. Fig. 2 represents a similar view of a modification of the upper part of the same. Fig. 3 represents a cross-section of an arm, taken just above one of the transverse pins; and Fig. 4, a longitudinal section of the lower part of said arm.

45 A designates the head of the doll; B, the upper or thigh part of its legs; C, the part thereof below the knee; D, the body; E, the detachable forearms; c, pins extending across the lower parts C of the legs, one to each; g,

similar pins crossing the lower sections E of the arms in the same way; d, Fig. 1, the fastening-wires of integral springs d', engaging pins c, and f the spring extending from arm to arm and engaging pins g. The legs and arms are hollow to receive said springs. The head and body are also hollow, the cavity of the latter communicating with the cavities of the arms and legs. A curved collar-piece l, forming a part of said body, receives the tapering rounded tubular neck A' of the head-piece A. The said collar-piece is centrally perforated at l'.

50 Two wires d, Fig. 1, are attached to the crown of the head A and extend down through the cavity of said head and neck and the hole or passage l' of said collar-piece. Then, diverging, they pass obliquely down through the cavity of the body to the right leg and left leg, respectively, the part of each wire which is in the leg and lower part of the body being 55 formed into a helical spring d'. This is not fastened at its lower end. If a lower joint C of a leg becomes detached, it is necessary only to slip it on the protruding end of said spring until the transverse rod c of said part C engages the said spring. Then turn the said section, and the rod will act on the spiral of the 60 spring as a nut would act on a movable screw and will stretch the spring in so doing. This is continued until the tension of said spring is sufficient to hold said part C securely in place. In case of separation at the hip-joint, 65 the upper part or thigh B of said leg is first slipped over said wire until it is in contact with the body D. The lower part C is then applied and turned, as before, the rod c serving to hold both sections, as well as the head 70 piece A, in place.

75 To attach the arms a continuous spring f, having its middle point in the middle of the said body D, extends in each direction into the cavities of detachable parts E E' aforesaid. In case of separation the method of reattachment is precisely the same as that before described, one of the pins g and the spring f acting like pin c and spring d' aforesaid.

80 The doll may be easily taken to pieces by turning the parts C and one or both of the parts E in the opposite direction from that 85 above referred to, the rod in each case of such 90

reversal unscrewing from the wire with which it engages.

In the modification shown in Fig. 2 the wires *d* are not attached to the crown of the head-piece, but to an attachment of the neck-piece *l*. This attachment consists of a plate *o*, extending across the opening *l'* and having points pressed downward into said neck-piece, and a short tube *p*, extending down through said opening, the latter being enlarged for that purpose. The wires *d* pass upward through holes *t* in said plate, one on each side of said tube, and are connected or united together above the latter.

15 The head *A* is attached to the body *B* independently of the legs by a spring *i*, the lower end of which is fast to a pin *j* on the inside of the body near said neck-piece, the upper part of said spring extending up into said head-piece through said tube *p* and passage *n* in continuation thereof. This passage is made centrally in a block *n*, on which the neck *A'* is fitted. At the upper end of said passage a pin *h* crosses it, the ends of said pin being pointed and bent down into the said block. This pin engages the said spring, and the turning of said head to one side or the other tightens the said head in place or loosens it for detachment, as aforesaid. The 25 middle part of spring *f* is shown as a straight wire; but the spirals may of course be continuous from end to end; also the part *f* may

be divided and the spring for each arm attached separately to the body, as in the case of the head, Fig. 2. The transverse pins or rods *c* may be of any convenient form, a part 35 properly located and capable of engagement with the spring, as described, being all that is needed. This means of fastening may be employed, also, in toys representing animals 40 or other jointed objects.

Having thus described my invention, what I claim as new, and desire to secure by Letters Patent, is—

1. In a toy, the combination of two hollow 45 detachable parts with a pin extending across the cavity of one of said parts, and a spiral spring engaging said pin and connected to the other part, substantially as set forth.

2. A doll or similar toy consisting of hollow 50 detachable jointed parts, in combination with pins and spiral springs normally inclosed in the cavities of said toy, the said pins and springs engaging to apply tension to said springs and thereby tighten said parts together when the parts provided with said pins are turned, substantially as set forth.

In testimony whereof I have hereunto signed my name in the presence of two witnesses.

ALBERT PULVERMACHER.
